UNITED STATES PATENT OFFICE

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA

DYEING APPARATUS

Application filed July 19, 1928, Serial No. 293,992.

This invention relates to dyeing apparatus, and more particularly to apparatus of this character in which the thread to be dyed is wound upon perforated cylindrical thread cores in the form of thread packages, and the cores with their packages are then mounted on a perforated dye liquor circulation pipe and disposed in a tank in such a manner that dye liquor may be circulated under pressure through the pipe, core and package, either outwardly or inwardly with respect to the pipe.

In apparatus of this character it is important to prevent leakage around the ends of the thread cores, and for this reason means have been provided to exert an axial pressure upon the ends thereof to effect the desired sealing. However, the action of heat may cause variations in length of the column during the dyeing process, causing gaps to form between the cores through which dye liquor may escape rather than through the thread packages, etc., especially where paper tubes or cores are utilized. Furthermore, while paper cores of satisfactory type are now available, these sometimes tend to soften under the action of hot dye liquor. This and other influences tend to cause change in axial dimension of the column, so as to dissipate the axial pressure originally imposed upon the cores and permit leakage which it has been the purpose to avoid.

It is therefore the object of the present invention to provide a follow up device for automatically taking up decrease or dissipation of pressure exerted upon an element mounted in a dyeing apparatus to prevent leakage around the end of the thread core.

Other objects and features of novelty will be apparent as the following description proceeds as taken in connection with the accompanying drawing, in which:

The single figure is a cross section through a dye liquor pipe showing the thread cores mounted thereon according to the present invention.

Referring more particularly to the drawing, the dye liquor circulation pipe is indicated generally at 10, and in the form shown is secured as by threading 11 to a dye liquor

circulation drum 12, the upper surface of which forms an abutment as at 13 to receive a spacer collar 14 which acts as a sealing element. Similar collars 15 and 16 serve to support perforated cylindrical thread cores 17 upon which have been wound thread packages 18 in substantially coaxial relationship with the dye liquor circulation pipe 10.

The cores may be each mounted on a separate dye liquor circulation pipe, but in the drawing they are shown mounted in tandem on a common pipe. Within the purview of the invention, the cores may be of rigid material and the sealing element may be yieldable, or the core may be yieldable and the sealing element rigid. Metallic cores have greater durability and can be used over many times, but they of course have greater weight. Paper cores have the advantage of inexpensive manufacture, and may be economically discarded after one use. The present invention is adapted for both of these expedients.

The outer end of the pipe 10 is provided with a closure 20 which in the form shown comprises a plug threaded as at 21 into the outer end of the pipe. The closure 20 is provided with a central bore 22 which slidably receives a plunger 23 extending inwardly into the pipe. This plunger is provided with a head or abutment 24 and a helical compression spring 25 surrounds the plunger 23 and bears at one end against the abutment 24 and at its other end against the inner side of the closure 20.

The outer end of the plunger 23 is threaded as at 28 to receive a cap indicated generally at 29. To prevent the plunger 23 from rotating with the cap 29 a slot 31 is cut part way through the closure 20, and a pin 32 carried by the plunger 23 rides in the slot 31 so as to permit sliding movement of the plunger. This cap 29 is provided with an annular abutment for exerting axial pressure upon the column of thread cores, which abutment in the present embodiment comprises an annular flange 30.

In operation, the cap 29 is unscrewed from the threads 28 and bodily removed. The thread packages having been previously wound upon the perforated thread cores, the

spacer member 14 is placed over the pipe 10 in position to bear against the abutment 13, and then the lower thread core is placed over the pipe 10 so as to abut against the spacer 14. 5 Then the spacer 15 is applied and then the upper core 17 with its thread package. Then the spacer 16 is applied and the cap 29 is threaded onto the threads 28, which will tend to draw the plunger 23 out of the pipe 10 against the action of the spring 25 so that the force of the spring 25 will be transmitted by the plunger 30 to the column of thread cores.

With this arrangement the pressure existing between the core and the sealing element will normally prevent leakage around the end of the core. But the seal may fail, due to weakening of the yieldable core, or the yieldable sealing element, by softening under the high pressures or temperatures of the dyeing process, or taking a permanent set. These conditions would dissipate the pressure upon the core and sealing element, initially imposed by the screw threads alone, 25 but the spring serves to automatically preserve the contact between the core and sealing element which would otherwise be broken.

The breadth of the invention is not to be limited to the embodiment disclosed, but is commensurate with the scope of the appended claims, and while the invention is described in detail for adaptation to dyeing apparatus, it is of general application where 35 it is of advantage to provide resilient pressure mounting for axially arranged elements.

Having thus described the invention, what is claimed as new and desired to be secured by Letters Patent is:

40 1. In a device of the class described, in combination, a member adapted to be rigidly secured to the free end of a perforated dye liquor circulation pipe, a second member having a portion encircling the pipe and adapted to exert pressure upon the end of a thread core also encircling the pipe, and means for constantly urging said second member toward the thread core, said means comprising a plunger connected to said second member 45 and extending through an aperture in the first member, and a spring operatively engaging the first member and the plunger.

50 2. The combination set forth in claim 1 in which said first member is formed as a cylindrical plug having threaded engagement with the inner wall of the dye pipe, and no portion of which projects beyond the outer wall of the pipe.

55 3. The combination set forth in claim 1 in which the said second member is formed as a hollow imperforate cap which constitutes a closure for the end of the adjacent thread core.

60 4. In a device of the class described in combination, a member adapted to be rigidly se-

cured to the free end of a perforated dye liquor circulation pipe, a second member having a portion encircling the pipe and adapted to exert pressure upon the end of a thread core also encircling the pipe, and means for constantly urging said second member toward the thread core, said means comprising a plunger connected to said second member and slidably extending through an aperture in the first member, said plunger having an abutment thereon and located within the dye pipe, and a compression spring having one end bearing against said abutment and its other end bearing against said first member.

65 5. In a device of the class described, in combination, a member adapted to be rigidly secured to the free end of a perforated dye liquor circulation pipe, a second member having a portion encircling the pipe and adapted to exert pressure upon the end of a thread core also encircling the pipe, and means for constantly urging said second member toward the thread core, said means comprising a plunger having threaded engagement with said second member and slidably extending through an aperture in the first member, the plunger and first member having cooperating elements which prevent relative movement thereof, and a spring operatively engaging said plunger and first member.

70 6. In a device of the class described, in combination, a member adapted to be rigidly secured to the free end of a perforated dye liquor circulation pipe, a second member having a portion encircling the pipe and adapted to exert pressure upon the end of a thread core also encircling the pipe, and means for constantly urging said second member toward the thread core, said means comprising a plunger having threaded engagement with said second member and slidably extending through an aperture in the first member, the plunger and first member having cooperating elements limiting the movement of the plunger into the pipe, and a spring having one end engaging the plunger and its other end operatively engaging said first member.

75 In testimony whereof I hereunto affix my signature.

CHARLES K. DUNLAP.
